UNITED STATES PATENT OFFICE.

CARL C. WARNER AND ELMER D. PAUL, OF HAVERHILL, MASSACHUSETTS.

TEMPLLET SCRIBE.

1,260,839.

Specification of Letters Patent. Patented Mar. 26, 1918.

Application filed January 22, 1917. Serial No. 143,737.

To all whom it may concern:

Be it known that we, CARL C. WARNER and ELMER D. PAUL, citizens of the United States, residing at Haverhill, in the county 5 of Essex and State of Massachusetts, have invented certain new and useful Improvements in Templet-Scribes; and we do declare the following to be a full, clear, and exact description of the invention, such as 10 will enable others skilled in the art to which is appertains to make and use the same.

Our invention has for its object to provide an improved device for marking the outline 15 of templets such as those used in grinding numerous kinds of knives having irregular cutting edges, and with this general object in view the invention resides in certain novel features of construction and in unique combinations of parts to be hereinafter fully described and claimed, the descriptive matter being supplemented by the accompanying drawings which constitute a part of this application and in which,

Figure 1 is a top plan view of the improved scribe;

Fig. 2 is a side elevation thereof;

Fig. 3 is substantially a central longitudinal section; and

Figs. 4 and 5 are vertical transverse sections respectively on the planes of the lines 4—4 and 5—5 of Fig. 3.

In the drawings above briefly described, the numeral 1 has reference to a flat horizontal base plate adapted to be supported 35 upon a bench or the like or in any other preferred manner. The opposite side edges of the plate 1 are provided with lateral extensions 2 from which a pair of cross-shaped templet holders 3 rise, the inner side of each 40 holder having a vertical groove 4 and a horizontal groove 5. The grooves 4 and 5 receive a pair of plates 6 and 7 respectively from which the templets are to be formed, said plates being secured in position by any suitable means such as the set screws 8. The 45 plates 6 and 7 are suitably treated on one side so as to permit the scribes hereinafter referred to to define a sharp line thereon.

Spaced toward one end of the plate from 50 the templet holders 3 are upright lugs 9 which are by preference formed integrally with said plate adjacent its opposite edges, set screws 10 being threaded through said lugs and having pointed inner ends 11 received in sockets 12 formed in other lugs 13

which depend from the ends of a gage plate holder 14 in the form of a plate extending transversely above the base plate 1, said holder 14 being adapted to receive on its upper surface a gage plate 15 having one 60 edge 16 of the required contour for guiding the scribes over the plates 6 and 7, screws 17 being preferably employed for securing the plate 15 in operative position. It will be obvious that by loosening the screws 10 the 65 angular relation of the holder 14 in respect to the base plate 1 may be varied, and that tightening of said screws will again lock said holder against further movement.

Spaced from the lugs 9 and extending 70 transversely across the upper surface of the base plate 1, is a guide rib 18 against which the inner edge of a slide 19 is adapted to contact, said slide resting on the plate 1 and being movable thereover. An arcuate 75 arm 20 rises from the slide 19 and is provided with a vertically disposed bearing 21 in which a vertical stem 22 is received for vertical adjustment, being held in adjusted position by a thumb screw 23. A slide 24 80 is mounted on the stem 22 and carries a scribe 25 adjustably secured in place by any suitable clamping means which is preferably equipped with a set screw 26. A coiled spring 27 surrounds the stem 22 between 85 the collar 28 on the upper end thereof and the slide 24, so that this slide is normally forced downwardly by the tension of said spring, for a purpose to be set forth.

Resting on the plate 1 near the end thereof 90 remote from the slide 19 is another slide 29 from which rises an arm 30 carrying a vertically disposed scribe 31 which is mounted for vertical adjustment and held in adjusted position by a set screw 32.

In operation, the two plates 6 and 7 are clamped in place by the set screws 8 and after first securing the gage plate 15 to the holder 14 the latter is adjusted to locate the curved edge 16 of said gage plate in proper 100 relation with both plates 6 and 7, as shown clearly in Figs. 1, 2 and 3. This having been done, the slide 19 is moved against the rib 18 and the horizontal scribe 25 is adjusted so that its point strikes the treated face 105 of the plate 6, said scribe then resting on the curved edge 16 of the gage plate 15. With the parts in this position, the slide 19 is moved back and forth across the plate 1 so that it duplicates the outline of the edge 16 on the 110

plate 6, the spring 27 causing the scribe to follow said edge.

After marking the plate 6, the latter is removed and the slide 29 is then shifted 5 along the base plate 1 so that the vertical scribe 31 comes in contact with the irregular edge 16 of the plate 15, as shown in dotted lines in Fig. 1. Said scribe is then adjusted to bring its point against the treated up- 10 per surface of the plate 7 and the slide 29 is then moved transversely across the base plate 1. The outline of the edge 16 will by this means be transferred to the horizontal plate 7, after which it will be removed. 15 The two plates 6 and 7 are then sheared and ground along the lines inscribed thereon, and may be used as templets for grinding irregular edged knives in the usual way, or they may be employed for forming mat- 20 rices for a grinding machine which constitutes no part of the present invention.

From the foregoing, taken in connection with the accompanying drawings, it will be obvious that the improved scribe will be 25 highly efficient regardless of its extreme simplicity and inexpensive construction, and for these reasons the arrangement of parts shown constitutes the preferred form of the device. It is to be understood, how- 30 ever, that within the scope of the invention as claimed, numerous changes may be made without sacrificing the principal advantages.

We claim:—

1. A templet scribe comprising a flat 35 horizontal base, a templet holder rising therefrom, a gage plate holder on the base adjacent said templet holder, a scribe support having a flat horizontal base slidable across said first named base, and a scribe 40 carried by said support to be moved along the templet and guided in its movement by a gage plate in said gage plate holder.

2. A templet scribe comprising a templet holder having means for holding a 45 pair of templet blanks, one in a vertical and one in a horizontal position, a gage plate holder adjacent said templet holder, a pair of scribe holders movable on opposite sides of said templet holder, a vertical scribe 50 carried by one holder for marking the horizontal blank, and a horizontal scribe carried by the other holder for marking the

vertical blank, both of said scribes being adapted for engagement with a gage plate to be secured to said gage plate holder. 55

3. A templet scribe comprising a base, a pair of spaced templet holders rising therefrom and each having in its inner side a vertical groove and a horizontal groove, said grooves being adapted to receive both 60 a vertical and a horizontal templet blank, a gage plate holder on the base to one side of the templet, a pair of scribe supports movable over said base on opposite ends thereof, a horizontal scribe carried by one 65 of said supports for engagement with a gage plate on the aforesaid gage plate holder to scribe the vertical templet blank, yielding means for permitting said scribe to move vertically to follow the gage plate, 70 and a vertical scribe carried by the other support for marking the horizontal templet blank.

4. A templet scribe comprising a base, a templet holder on said base for holding a 75 vertical templet blank, a gage plate holder to one side of said templet holder, a slide resting on the base adjacent said gage plate holder, a vertical stem carried by said slide, a slide on said stem, a horizontally extending 80 scribe carried by said last named slide for engagement with the templet blank and a gage plate carried by the aforesaid holder, and a spring surrounding said stem and bearing against said last named slide for 85 so moving the same as to retain the scribe in contact with the gage plate.

5. A templet scribe comprising a flat horizontal base, a templet holder thereon having means for holding a horizontal templet blank, a scribe support having a flat horizontal base resting slidably on said first 90 named base, a vertical scribe carried by said scribe support for marking the templet, and a holder on the base for carrying a gage 95 plate to guide said scribe.

In testimony whereof we have hereunto set our hands in presence of two subscribing witnesses.
